UNITED STATES PATENT OFFICE.

ROBERT WADDELL, OF SEATTLE, WASHINGTON, ASSIGNOR TO WASHINGTON IRON WORKS COMPANY, OF SEATTLE, WASHINGTON, A CORPORATION OF WASHINGTON.

POWER STEERING APPARATUS.

1,184,283.

Specification of Letters Patent. Patented May 23, 1916.

Application filed May 10, 1915. Serial No. 27,106.

To all whom it may concern:

Be it known that I, ROBERT WADDELL, a subject of the King of England, residing at Seattle, in the county of King and State of Washington, have invented certain new and useful Improvements in Power Steering Apparatus, of which the following is a specification.

This invention relates to power actuated steering apparatus for marine vessels; and its object is the improvement in apparatus of this character to render the same more efficient in operation and wherein the rudder is automatically held in adjusted positions.

The invention consists in the novel construction, adaptation and combination of parts, as will be hereinafter described and claimed.

In the accompanying drawings, Figure 1 is a plan view, shown somewhat diagrammatically, of a boat with my invention applied thereto. Fig. 2 is a longitudinal vertical section of the power and braking devices of the steering apparatus.

Referring to the drawings, the numeral 5 designates a steam cylinder arranged in axial alinement with a liquid containing cylinder 6 to which it is rigidly connected by the bars 7 and 8, constituting a frame 30 which is secured, as by bolts 9, extending through flanged elements 10 of the respective cylinders, to the deck beams 11 of a vessel.

12 represents a peripherally grooved sheave rotatably mounted in a carrier 13 provided with guide boxes 14 for the bars 7 to afford longitudinal movements to the carrier.

The piston rods 15 and 16 for the pistons 40 15¹ and 16¹ of the steam and liquid cylinders are keyed or otherwise rigidly secured to said carrier. Passing about the sheave 12 is the tiller cable having leads 17 extending about guide sheaves 18 to the barrel of 45 steering wheel 19. The other leads 17¹ of said cable are guided by sheaves 18¹ to and connected with the sector-shaped tiller 20 on the post of rudder 21.

By such devices the rudder may be influenced manually through the agency of the steering wheel 19 or by means of the power devices or the agency of the steam cylinder.

The steam passages 22 of the cylinder 5

are controlled by a slide valve 23 of ordinary 55 or suitable construction. The valve stem 24 is connected by a coupling 25 to a controller rod 26, to cause them to be movable axially in unison but enable the rod to be rotated independently of the valve stem. Said rod 60 passes through the valve chamber 27 of the liquid cylinder 6 and therebeyond is formed with a screw-thread 28 which engages the internal thread provided in the hub 29 of a bevel tooth gear 30. The latter is journaled 65 and secured against endwise movement in a bracket 31 provided on the cylinder 6.

In mesh with the gear 30 is a complementary gear 32 mounted upon a shaft 33 upon which is a grooved pulley 34 whereby rotary motion may be imparted to the shaft 70 through the medium of an endless belt 35 passing about a pulley 36 provided on the axle of supplementary steering wheel 19¹. Passages 37 and 37¹ connect the ends of the 75 liquid cylinder 6 with the ends of said valve chamber for the flow of liquid through such chamber from opposite sides of the piston 16¹ when axial movement is afforded thereto. In proximity to the mid-length of the valve 80 chamber are two spaced seats 38 and 39 for valves 38¹ and 39¹ which are yieldingly held upon such seats by helical springs 40 and 40¹ supplemented by the pressure of the liquid obtaining at the ends of valve chamber 85 and in the communicating ends of cylinder 6. These valves are slidably mounted on the rod 26 which is provided therebetween with a collar 41. Said rod is also provided with a screw-thread 42 of great pitch engaging a nut 43 fixedly secured to or made integral with the carrier 13, which, upon being reciprocated, will serve to rotate the rod.

44 represents a pipe connecting the chamber 27 between the valve seats with a tank 95 45 to accommodate the liquid displaced by the piston rod 16 when the piston 16¹ is moved in one direction.

The operation of the invention is as follows: When the steersman, through the 100 medium of the manually actuated part of the mechanism, including the belt 35, shaft 33 and gear 32, rotates gear 30, the screw thread within the latter serves to effect an endwise movement to the rod 26 and its collar 41 and also of the valve stem 24 whereby the valve 23 is influenced to uncover a port 105 of one of the passages 22 to admit steam into

an end of the cylinder 5. When, for example, said valve is moved into the position in which it is represented in Fig. 2, the steam will force the piston 15¹ toward the 5 left hand side of the referred to view accompanied by the sheave carrier 13 and the brake piston 16¹. The carrier being thus moved, will effect the swerving of the rudder through the instrumentality of the 10 sheave 12 and the tiller lines, as will be understood. The liquid in advance of the then moving piston 16¹ is forced through passage 37 into and through the chamber 27 and thence returned through passage 37¹ to 15 the other end of cylinder 6.

To accommodate such by-passage of the liquid the valve 38¹ has, through the agency of the collar 41, been dislodged from its seat 38 while the other valve 39¹ is pushed 20 from its seat by the liquid pressure overcoming the power of the spring 40¹.

When motion is imparted to the carrier 13, as above explained, the nut 43 connected thereto acting through the agency of screw 25 42, rotates the rod 26 whereby the same is screwed into the hub of gear 30 to restore the valve 23 to its closed position with respect to both of the cylinder passages 22 and likewise withdraws the collar 41 from 30 valve 38¹ whereupon the spring 40 asserts its power and seats this valve. This being accomplished, the flow of liquid between the ends of cylinder 6 is interrupted, resulting in the stopping of any further axial movement 35 of the piston 16¹ and the carriage 13 to accordingly hold the rudder in adjusted position.

Where the rudder is to be swung over through a considerable angle, the steersman 40 would continue to turn the steering wheel, which controls the rotation of the gear 30 to compensate for the rotation of the rod 26 due to the travel of nut 43 upon screw 42. In such action, it is to be understood that 45 simply a turning effect is exercised by nut 43 upon the rod 26 while the axial movements thereof are attained by the screw 28 being screwed into or out of the gear 30 which may be rotated to neutralize any axial travel of the rod.

Among the advantages afforded by this invention is the coöperative action of the steam and liquid controlling valves, to regulate the operations of the power and brake 55 devices and impart steering movements to the rudder, as well as holding the latter in adjusted positions.

The tiller-line controlling sheave 12, upon being moved by the power devices, regulates 60 the rudder and is free to rotate when it is desirable to steer by the manually actuated wheel 19.

What I claim as my invention, is—

1. In power steering apparatus, the combination with a controlling sheave, guide

pulleys, and the tiller lines passing about 70 said sheave and pulleys, of a carrier for said sheave, a steam cylinder, a liquid cylinder, piston rods therefor which are connected to said carrier, a by-pass between the ends of said liquid cylinder, normally closed 75 valves for said by-pass, a valve for the passages of the steam cylinder, means under the control of the steersman whereby the valves may be regulated to afford reciprocatory movements to the carrier through power derived in said steam cylinder, and means influenced by the travel of said carrier whereby the by-pass valves are rendered operative to confine liquid in the cylinder 80 therefor whereby the travel of the carrier is arrested.

2. In apparatus of the class described, a steam cylinder, a liquid cylinder having by-pass connections between its ends, a sheave 85 carrier, pistons for the respective cylinders, piston rods therefor which are rigidly connected to said carrier, valves for regulating the flow of liquid through said by-pass, a rod adapted for endwise movements to unseat either of said valves, means to effect such movements of the rod in either direction selectively, said rod being provided with screw threads, and means operated by the movements of said carrier and through 90 the instrumentality of said screw-threads to render said valves operable to shut off the flow of liquid through said by-pass whereby the travel of the carrier is interrupted.

3. In apparatus of the class described, the 100 combination with a steam cylinder, a liquid cylinder having a by-pass connecting its ends, pistons for the respective cylinders, and connections between said pistons to cause them to move as a single element, of 105 spaced valve seats provided in said by-pass, spring closing valves for said seats and arranged to be openable toward the adjacent ends of the by-pass, manually controlled means for opening either of said valves for 110 the flow of liquid from one end of its cylinder to the other to render the power agent within the steam cylinder capable to impart movement to said pistons, and means rendered operative by such produced piston 115 movement to cause the first named means to become temporarily inoperative to retain the previously affected valve in open position.

4. In apparatus of the class described, a 120 power cylinder and a brake cylinder secured in axial alinement with each other, pistons for each of said cylinders, operative connections between said pistons to cause them to move in unison, a sheave, a carrier 125 therefor secured to said piston connections, a by-pass chamber communicating with the ends of said brake cylinder and provided intermediate its length with two spaced valve seats, valves for the respective seats, 130

5 springs tending to yieldingly retain said valves against their seats, a valve for said power cylinder, a nut connected to said carrier, a manually rotatable nut secured against axial movements, a rod operatively connected with the last named valve and provided with means engageable with either of the first named valves to open the same, said rod being provided with screw-threads 10 engaging with the respective nuts whereby the rotation of the manually rotated nut will effect axial movements to the rod to render the power agent operative to move said carrier, whereupon the nut associated with the latter will act to render the spring of the previously opened first-named valve capable of closing the same.

20 5. In apparatus of the class described, the combination with a steam cylinder and a liquid cylinder, pistons for said cylinders, a tiller-line sheave connected with both of said pistons to move therewith, valves for the respective cylinders, manually actuated means for opening valves of both cylinders 25 to afford movements to the pistons thereof for the travel of said sheave, and means actuated by such movements of the pistons whereby the valves are closed to arrest the

travel of the sheave through the agency of the liquid within said liquid cylinder. 30

6. In power steering apparatus, the combination with the steam cylinder and the liquid cylinder, the pistons for the respective cylinders, piston rods therefor, the tiller-lines, a sheave for said lines, a sheave carrier secured to said piston rods, of a valve for the passages of said steam cylinder, spring closing valves for passages connecting the opposite ends of the liquid cylinder, a rod operatively connected with the first named 40 valves and adapted to engage selectively either of the last named valves, manually actuated means to effect the operative movements of said rod, and means provided on the carrier and engageable with said rod 45 whereby the latter is influenced by the operative movements of the carrier to cause said rod to be capable of closing the steam valve and render it temporarily inoperative with respect to both of the spring-closing 50 valves.

Signed at Seattle, Washington, this 17th day of April, 1915.

ROBERT WADDELL.
